UNITED STATES PATENT OFFICE.

WALTER O. SNELLING AND WILLIAM R. LAMS, OF ALLENTEWON, PENNSYLVANIA,
ASSIGNORS TO TROJAN POWDER COMPANY, OF ALLENTEWON, PENNSYLVANIA,
A CORPORATION OF NEW YORK.

METHOD OF MANUFACTURING NITROSTARCH EXPLOSIVES.

1,329,212.

Specification of Letters Patent. Patented Jan. 27, 1920.

No Drawing. Original application filed June 22, 1918, Serial No. 241,354. Divided and this application filed September 8, 1919. Serial No. 321,455.

To all whom it may concern:

Be it known that we, WALTER O. SNELLING and WILLIAM R. LAMS, citizens of the United States, and residents of Allentown, Lehigh county, Pennsylvania, have invented certain Methods of Manufacturing Nitrostarch Explosives, (being a division of application Serial No. 241,354, filed June 22, 1918,) of which the following is a specification.

10 Our invention relates to organic nitrate explosives and more particularly to nitro-starch explosives and their manufacture.

The problem of stabilizing nitro-starch in the preparation of nitro-starch explosives 15 presents difficulties, by reason of the fact that certain organic bodies well recognized as among the best stabilizing agents for other nitro-explosives, have not been usable with nitro-starch without injurious effect

20 upon the explosive. Nitro-starch is very readily colloided by a large number of organic substances, and such colloidization, even when it is only superficial and does not extend materially into the substance of the

25 nitro-starch granules, acts injuriously upon the nitro-starch. The stability of nitro-starch which is partly colloided is usually much less than is the corresponding stability of the uncolloided nitro-starch, and the sensitivity to detonation is also influenced, 30 colloided nitro-starch being much more difficult to detonate than uncolloided nitro-starch, thus making the use of a very strong detonator necessary, where any considerable amount of colloidization has occurred.

35 There are certain substances, such as rosanilin base, and diphenylamin, which are well recognized as stabilizing agents in connection with nitro-cellulose products. Owing to the greater ease with which nitro-starch tends to colloid, the introduction of these materials into the manufacture of nitro-starch explosives has been limited, and accordingly the use of these valuable stabilizing agents has in a measure been prevented.

40 We have discovered that the presence of a heavy mineral oil, such as a medium or heavy lubricating oil, tends to wholly prevent the colloiding action of basic stabilizing agents, without lessening in any way their stabilizing properties. It appears that the oil acts as a protection against colloid-

ization of the nitro-starch, the oil probably covering the surface of the nitro-starch 55 granules with a thin film, and this film of oil-saturated nitro-starch resisting the colloidizing action of the stabilizing agent.

In the practice of our invention, we use only small amounts of oil, and very small 60 amounts of the stabilizing agent. For example, with a finished explosive containing 25% of nitro-starch, and a total of about 70% of sodium and ammonium nitrates, we may use from one-half of one per cent. to a 65 total of about 2% of oil, and of stabilizing agent from about one-tenth to three-tenths per cent.

As an illustration of a nitro-starch powder made up according to the present invention. 70 we give the following formula:—

Nitrated starch	25.0%
Ammonium nitrate	33.0%
Sodium nitrate	38.2%
Charcoal	2.0%
Sodium bicarbonate	.5%
Oil	1.0%
Diphenylamin	.3%
	100.0%

80 In our application Serial No. 241,354 filed June 22, 1918, of which this application is a division, we have described a method of treating the nitro-starch with the stabilizing agent by dissolving the said agent in the oil and then incorporating the solution with the other ingredients of the explosive. According to our present invention the diphenylamin, free from oil, is added to the inorganic nitrate such as sodium nitrate, or the mixture of sodium and ammonium nitrates, 85 said mixture being heated, and the heated mixture rolled or tumbled for some time at a temperature preferably of about 50° C., or 90 higher. Diphenylamin being slightly volatile at this temperature, coats the grains of nitrate. Nitro-starch previously mixed with a sufficient quantity of a heavy mineral oil to coat the nitro-starch particles with a 95 thin film of said oil is then thoroughly mixed with the treated inorganic nitrate, and the oil serves its function of protecting the nitro-starch grains from the colloidizing effect of the diphenylamin.

100 105 By referring in our specification to di-

phenylamin as a suitable stabilizing agent for the practice of our invention, we do not, in its broader aspects, wish to be limited to that particular agent, as other stabilizing agents having colloiding properties may be successfully employed with nitro-starch by the method above outlined—such for example as other organic bodies containing an amino group. The colloiding action is prevented by the presence of mineral oil.

As to the mineral oil, we have obtained satisfactory results with medium or heavy lubricating oil, but do not wish to be limited to this as other suitable heavy mineral oils may readily be substituted and are available on the open market.

We claim:

1. The method of treating nitro-starch which consists in providing the nitro-starch particles with a minute film or coating of a heavy mineral oil and acting thereon with an organic stabilizing agent soluble in said mineral oil.

2. The method of manufacturing nitro-starch explosives containing an inorganic nitrate and an organic stabilizing agent, which consists in thoroughly mixing the nitrate with the stabilizing agent at a temperature sufficiently high to slightly volatilize the latter, thereby coating the nitrate grains with said organic body and then thoroughly mixing with said treated nitro-starch in the presence of a small quantity of mineral oil.

3. The method of manufacturing nitro-

starch explosives containing an inorganic nitrate which consists in thoroughly mixing the nitrate with an organic stabilizing agent containing an amino group at a temperature sufficiently high to slightly volatilize the latter thereby coating the nitrate grains with said organic body, and then thoroughly mixing with said treated nitrate, nitro-starch in the presence of a small quantity of mineral oil.

40

45

4. The method of manufacturing nitro-starch explosives containing an inorganic nitrate which consists in thoroughly mixing the nitrate with diphenylamin at a temperature sufficiently high to slightly volatilize the latter, thereby coating the nitrate grains with said diphenylamin, and then thoroughly mixing with said treated nitrate nitro-starch in the presence of a small quantity of mineral oil.

50

55

5. The method of manufacturing nitro-starch explosives containing an inorganic nitrate which consists in thoroughly mixing the nitrate with diphenylamin at a temperature sufficiently high to slightly volatilize the latter, thereby coating the nitrate grains with said diphenylamin, mixing nitro-starch with a sufficient quantity of a heavy mineral oil to coat the nitro-starch particles with a thin film of said oil, and then thoroughly mixing together the treated inorganic nitrate and the treated nitro-starch.
